CLAIM

The ornamental design for a lighting fixture, as shown and described.

DESCRIPTION

FIG. 1 is a perspective view showing a new design for a lighting fixture angled rearward approximately 15 degrees from vertical;

FIG. 2 is a front view of the lighting fixture of FIG. 1; FIG. 3 is a bottom view of the lighting fixture of FIG. 1; FIG. 4 is a perspective view of the lighting fixture of FIG. 1 angled rearward approximately 30 degrees from vertical; and,

FIG. 5 is a perspective view of the lighting fixture of FIG. 1 angled rearward approximately 45 degrees from vertical.

(Continued)

The broken lines shown on the drawings depict portions of the light fixture that form no part of the claimed design.

1 Claim, 3 Drawing Sheets
